EXPANSIBLE LINK CHAIN FOR A BRACELET
OR THE LIKEEmil Rodriguez, New York, N. Y., assignor to
Jacoby-Bender, Inc., New York, N. Y., a corpora-
tion of New York

Application January 5, 1950, Serial No. 7,009

Term of patent 7 years

(CL. D45—4)

To all whom it may concern:

Be it known that I, Emil Rodriguez, a citizen of the United States and a resident of New York, county and State of New York, have invented a new, original, and ornamental Design for an Expansible Link Chain for a Bracelet or the like, of which the following is a specification, reference being had to the accompanying drawing forming a part thereof, in which:

Fig. 1 is a top view of the expansible link chain, showing my new design in contracted condition;

Fig. 2 is a top view thereof in partially expanded condition, portions of the conventional bottom links being visible between the top links;

Fig. 3 is a side elevational view of one of the individual top links of the chain of Fig. 2; and

Fig. 4 is an end elevational view of the individual top link of Fig. 3.

I claim:

The ornamental design for an expansible link chain for a bracelet or the like, as shown.

EMIL RODRIGUEZ.
